JOHN H. GOEHST AND RALPH G. CARPENTER, OF CHICAGO, ILLINOIS, ASSIGNEES TO
FEDERAL ELECTRIC COMPANY, OF CHICAGO, ILLINOIS, A CORPORATION OF ILLI-
NOIS.

DESIGN FOR A KITCHEN-CABINET.

41,096.

Specification for Design.

Patented Jan. 17, 1911.

Application filed August 25, 1910. Serial No. 578,974. Term of patent 14 years.

To all whom it may concern:

Be it known that we, JOHN H. GOEHST and RALPH G. CARPENTER, citizens of the United States, and residents of the city of Chicago, county of Cook, and State of Illinois, have invented a new, original, and ornamental Design for Kitchen-Cabinets, of which the following is a specification, reference being had to the accompanying drawings, forming part thereof.

The figure of the drawing is a perspective

view of a kitchen cabinet showing our new design.

We claim:—

The ornamental design for a kitchen cabinet as shown.

JOHN H. GOEHST.
RALPH G. CARPENTER.
